WALLPAPER PASTING DEVICE

John S. Drienka, Chicago, Ill.

Application January 25, 1946, Serial No. 643,227

3 Claims. (Cl. 91—14)

1

My invention relates to wall-papering devices. An important object of my invention is to provide a compact device, in which a roll of wall paper may be removably, and interchangeably, mounted, containing suitable means for applying the glue as the paper is unrolled therefrom, for application to a wall or ceiling surface of a room.

Another object of my invention is to provide optionally usable cutter means, for cutting off a portion of the width of the wall paper, simultaneously with, its being unwound from the roll.

Another object of my invention is to provide, in a device of the aforementioned character, means for cutting off transversally a sheet of wall paper to suitable length, and to which glue has been simultaneously applied.

A still further object of my invention is to provide simple rod support means for supporting an optionally usable cutter, and novel means for quickly locking and unlocking the said rod support in its place.

A still further object of my invention is to provide glue distributing means, consisting of a notched roller, a substantial portion of the said roller being submerged in the glue container.

A further object of my invention is to provide simple, and effective, locking means for the spindle supporting the roll of wall paper.

A still further object of my invention is to provide, a simple device of the aforementioned character, which is practical in construction, efficient in its use and operation, and of such simple elemental structure as to warrant economical manufacture thereof, in quantity production.

Other features, and objects, of my invention will become clearly exemplified from reference to the accompanying drawing embracing the various structural features of my invention, and bearing further elucidation in the ensuing description, wherein like symbols are used to designate like parts, and in which;

Fig. 1 represents a perspective view of my invention with certain portions thereof broken away, so as to more clearly depict the structural details thereof.

Fig. 2 is a perspective view indicating the removal of the upper guide roller to facilitate filling the glue pot, or well, with suitable gum or paste.

Fig. 3 is a perspective view of my invention showing the interchangeability feature, which permits of readily and instantly mounting rolls of paper when necessary.

Fig. 4 is a fragmentary end view showing the locking mechanism for the wall-paper roll supporting spindle.

Fig. 5 is a fragmentary perspective view, showing the locking mechanism for the guide roller, which also supports in articulate, and radial ad-

justment, the cutter which may be optionally used.

Fig. 6 is a fragmentary perspective view showing the structural details of the fractional or sectional wall-paper cutting device.

Fig. 7 is a schematic view, showing how the edge of the roll of paper is laced through the guide rollers, and the feed rollers of my invention, also showing how an edge thereof is utilized for cutting off lengths of wall-paper.

Fig. 8 is a perspective view, indicating how my device may be used to apply a sheet of wall-paper to a ceiling of a room.

Fig. 9 indicates how lengths of wall-paper are secured to a wall surface of a room, and;

Fig. 10 indicates how a section of the width of the wall-paper is being cut for application to a portion of a wall, next to the corner of a room, only a fractional part of the wall-paper being essential, to form a continuous pattern.

Referring to the various views, my invention is, generally, designated 11 and it consists of a base 38 of wood, or other like material, on which may be mounted the body consisting of a U-shaped bracket formation, having a base portion 12, and upright sides 13 and 14, in which the structural mechanism comprising my invention is removably and interchangeably mounted. The upright sides 13 and 14 at the rear are interconnected by the back portion 23.

Referring to Figures 1 to 7, it will be noted, that I provide a roller or spindle 21 for supporting a roll of paper 24, the upper edge 25 thereof being laced over the roller 37 and under the guide rod 26, and over the guide rod 27; then it is laced under the upper guide roller, that is between the upper guide roller 19, and the glue distributor 37. The upper roller 19 is urged into contactual relationship with the outer periphery of the glue distributor roller 37 by means of the springs 20, each spring 20 having one of its ends anchored to the spindle 15 supporting the roller 37, the other end being anchored to the end bearing support 18 of the roller 19. The said bearing supports 18 operate in the slots 17, and are supported by the bottom portion thereof, the springs holding the said roller 19 in contactual frictional relationship with the roller 37. Thus the roller 19 may be removed by moving the portions 18 out of the slot 17, and unhooking the upper anchorage of the spring 20, whenever it is desired to feed the edge of the paper 25 therethrough.

The wall-paper spindle 21 is provided with a headed portion 22, which acts as a stop when the same is inserted in proper bearings in the sides 13 and 14, and a simple articulate locking means is provided, which consists of one enlarged portion 29, mounted on a pivot pin 28, and having a handle 30, the same being actuated in rotative,

or arcuate direction, for covering the headed portion 22, or uncovering the same when it is either desired to hold the spindle in place, or when it is desired to remove it from assembly, preparatory to mounting a new roll of paper thereon.

The guide rod 27 also serves another purpose for mounting the cutter that may be optionally used, and which is adjustable arcuately about the rod 27 as indicated in Figure 1. It is to be noted, that the rod 27 is provided with a hooked portion 31, which has contiguously thereto, a knee or bent portion 32, terminating in a manipulating handle 33, so that the same may be brought into locking engagement with the side 14 in the support, or may be rotated out of engagement as shown by the dotted lines of Figure 5, which permits removal of the said rod whenever necessary.

The cutter, referring to Figure 6, consists of a holder body 41, which is slidably mounted on the rod 27, and a screw 42 with a soft tip is provided, for clamping the same in lateral adjusting relationship, as well as operative or inoperative position by rotating the same about the rod 27, bringing the point of the knife 44 into position for cutting, or into idle position when cutting is not desired. The body 41 is provided with an upward extension 43, on which the knife 44 may be spot welded, or secured in interchangeable arrangement, so that when the knife becomes dull the same may be removed, and replaced by a sharp knife, or it may be sharpened and replaced.

In Fig. 7, I indicate how the roll of paper is mounted in my device, preparatory to its actual use. It will be noted, that I provide a rear cutting edge portion which in no way interferes with the feeding of the paper as needed, and when proper length has been fed, the lower portion thereof may be bent as indicated at 53, and by a gentle pulling action against the cutting edge 40 the entire section or length of paper may be transversely cut at 39 and positioned on a wall.

The distributor roller 37 is provided with a series of longitudinal notches 16, which operate in the well 36, which contains the glue thus limiting the amount of glue that can be picked up by the peripheral surface of the roll 37. The said notches 16 thus provide sufficient application of glue to the wallpaper, not allowing too much, nor too little, to be placed thereon, especially by virtue of the frictional and spring urged contractual relationship of the roller 19 with the peripheral surface of the roller 37, the roller having a tendency to squeeze or press out any excess glue that may be picked up by the paper, thus furnishing ideal conditions for wall-papering.

The glue may be poured into the well 36, by using a pot 34 containing the material, and pouring the glue 35 thereinto as indicated in Figure 2, where the roller 19 has been removed, so as to facilitate that operation, and so as to prevent the upper roller 19 from becoming contaminated with adhesive.

When it is desired to cut a longitudinal section of paper as indicated in Figure 1, the cutter may be adjusted to the position shown by the dotted lines, thus causing the paper to be severed, simultaneously, with the pulling thereof through the device.

In Figure 8, I show, how my invention may be used when held in one hand to apply a section of wall-paper to a ceiling 51, the other hand

holding the brush 45 which is customarily used by paper-hangers in their work, to make certain that the paper is adhering to the surface of the wall or ceiling to which it is applied.

In Figure 9, I show how my device may be conveniently placed on the floor, next to the base board 52 of a wall 49, and a length of wall-paper is pulled up to align and be positioned at the ceiling line. When it is desired to sever the length of wall-paper, it is cut as indicated in Figure 7, and it is usually cut to a slightly longer length than needed to meet the top of the base board, so that the length of paper can be suitably attached to the wall, and the excess can be cut off with an ordinary knife, or other cutter so as to assure that the distance between the ceiling and the base board 52 has been covered.

After the wall 49 is covered with several lengths of paper, and an increment of space 47 between the edge of the last length of paper covered, and the corner of a room 50, the increment 47 being less than the width of the sheet, the cutter 44 is set into operation, so that simultaneously with the pulling of the reduced width section 46, the proper width of paper may be taken, which is also cut at a point to match the pattern indicated, the remaining sheet of paper may be saved for use elsewhere.

When it is desired to change a roll of paper, the locking device 29 is rotated to the dotted position of Figure 4 by manipulating the handle 30 thereof, thus exposing the headed portion 22, permitting removal of spindle 21 and insertion into the core of a roll of wall-paper 24, and then the locking device actuated to the full lines indicated at Figure 4. When it is desired to remove the cutter bar, in order to permit removal of the cutter, Figures 5 and 6 illustrate how that may be accomplished, namely, by loosening the set screw 42, then rotating the handle 33 to the dotted position, pulling the same out, thus permitting removal of the cutter from the free end of the axle 26.

The device is useful in covering walls, ceilings, and other similar surfaces of regularly shaped rooms, or irregularly shaped rooms.

Having thus disclosed and revealed my invention what I claim as novel and desire to secure by Letters Patent, is:

1. A device of the character described comprising, a frame-work, a paper roll supporting spindle removably mounted in the said frame-work, articulate locking means secured to the said frame-work and arranged to releasably lock the said supporting spindle, outer and inner guide rods forming a pair of wall-paper guide rods spaced apart in substantially superimposed relationship mounted in the said frame-work above the said supporting spindle, a glue reservoir mounted in the said frame-work adjacent the said guide rods, glue distributing means rotatably mounted in the said glue reservoir, a mating feed roller removably mounted in the said frame-work and resiliently urged into contacting relationship with the said glue distributing means, and sectional piercing knife means adjustably and articulately mounted on the outer of the said guide rods and adapted to cut off a fractional width of wall-paper when in its operative position and further adapted to be swung arcuately to inoperative position.

2. A device of the character described comprising, a frame-work, a paper roll supporting

spindle removably mounted in the said frame-work, articulate locking means secured to the said frame-work and arranged to releasably lock the said supporting spindle, outer and inner guide rods forming a pair of wall-paper guide rods spaced apart in substantially superimposed relation mounted in the said frame-work above the said supporting spindle, a glue reservoir mounted in the said frame-work adjacent the said guide rods, glue distributing means rotatably mounted in the said glue reservoir, a mating feed roller removably mounted in the said frame-work and resiliently urged into contacting relationship with the said glue distributing means, and sectional piercing knife means adjustably and articulately mounted on the outer of the said guide rods and adapted to cut off a fractional width of wall-paper when in its operative position and further adapted to be swung arcuately to inoperative position, the rear portion of the said frame-work terminating in an upper cutting edge to facilitate cutting varied lengths of paper.

3. A device of the character described comprising, a frame-work, a paper roll supporting spindle removably mounted in the said frame-work, articulate locking means secured to the said frame-work and arranged to releasably lock the said supporting spindle, outer and inner guide rods forming a pair of wall-paper guide rods spaced apart in substantially superimposed relationship mounted in the said frame-work above the said supporting spindle, a glue reservoir mounted in the said frame-work adjacent

the said guide rods, glue distributing means rotatably mounted in the said glue reservoir, a mating feed roller removably mounted in the said frame-work and resiliently urged into contacting relationship with the said glue distributor means, and sectional piercing knife means adjustably and articulately mounted on the outer of the said guide rods and adapted to cut off a fractional width of wall-paper when in its operative position and further adapted to be swung arcuately to inoperative position, the said outer guide rod provided with S-shaped instantaneous securing means adapted to engage an upright edge of the said frame-work to releasably lock the said outer guide rod to the said frame-work.
